UNITED STATES PATENT OFFICE.

WILLIAM F. RILEY HARTLEY, OF PHILADELPHIA, PENNSYLVANIA, ASSIGNOR
TO BARNES & BEYER, OF SAME PLACE.

DESIGN FOR A CURTAIN.

SPECIFICATION forming part of Design No. 18,883, dated January 29, 1889.

Application filed January 3, 1889. Serial No. 295,340. Term of patent 3½ years.

To all whom it may concern:

Be it known that I, WILLIAM FRANCIS RILEY HARTLEY, a citizen of the United States, residing at Philadelphia, in the county of Philadelphia and State of Pennsylvania, have invented and produced a new and original Design for a Chenille Curtain, of which the following is a specification, reference being had to the accompanying photographic print, forming a part thereof, which conveys to any one skilled in the art of chenille-weaving a clear understanding of the same, and is sufficient to enable such person to use my invention.

The photographic print shows but a portion 15 of the side borders and center. That part of the borders and center not shown is the repeat of the ornamentations that are shown.

What I claim as my invention, and desire to secure by Letters Patent, is—

The design for a chenille curtain, consisting in the ornamentations shown in the photographic print accompanying this specification.

WILLIAM F. RILEY HARTLEY.
